UNITED STATES PATENT OFFICE.

LEON CHARLES DEOUNE, OF MARSEILLE, FRANCE, ASSIGNOR TO SOCIETE ANONYME
DES ATELIERS ARMAND & DEOUNE, A COMPANY OF FRANCE.

AUTOMATIC HYDRAULIC PRESS.

Application filed November 5, 1926, Serial No. 146,504, and in France November 26, 1925.

The invention relates to an automatic hydraulically operated press for the extraction of oils from seeds or fruit in which the admission and exhaust of the pressure on the 5 different pistons, the insertion of the filtering fabric or fabrics, the ejection of the oil cake from the press and the setting of the press for a new cycle of operations are automatic.

10 The invention consists in the filtering fabric being arranged in front of a bed for the movable pressure chamber and in means for moving said fabric out of the pressure chamber together with the pressed oil cake. Furthermore according to the invention the ram 15 after having pressed the oil cake begins its backward motion first, and then the pressure chamber returns to its initial position, the speed of the pressure chamber exceeding the 20 speed of the ram.

The apparatus as invented includes the following advantages:

Speedy extraction of the liquids.

25 Eliminates the loose sheets or absorbing materials in which the matter to be pressed is sometimes wrapped.

Elimination of the "parings" or edges of the oil-cakes not completely exhausted.

30 Renders useless the so-called "preparatory" presses.

Possibility of treating any matter out of which the liquid parts are to be extracted; the liquid obtained being in every case quite clear and pure.

35 Possibility of altering the pressure exerted, and the time during which it is applied, according to the result desired.

Very high pressure.

Elimination of considerable labour.

40 The attached drawings show a preferred embodiment of the invention, in which,

Fig. 1 is a part elevation, part vertical section of the whole of the press and of its accessory parts.

45 Fig. 2 is a cross view with part-section through the casing E for one half and through the casing F for the other half.

Fig. 3 is a vertical section of an alternative construction of the piston-head I.

50 The apparatus comprises:

A framework A supporting a cylinder B and a bed C stayed by two columns D.

A filtering metal casing composed of two parts E and F, slides on the columns D.

55 This metal casing can be brought against the

bed C, by means of the pistons G placed symmetrically to the horizontal axis of the press.

The pistons H, with invariable pressure tend to hold the casing E, F away from the 60 bed C; the action of the pistons G being more powerful when they receive the hydraulic pressure, the casing F is pressed against the bed C.

A pressing piston I slides inside the cylinder B, and is brought back by the rods K connecting it with the constant pressure cylinder J sliding on the piston L when the pressure of the piston I is shut off.

The piston I enters the portion F of the 70 casing to compress the material to be treated placed against the filtering fabric T itself placed next to the perforated plate Q.

The portion E of the casing has an inner 75 annular perforated wall E¹, the holes in which lead into a circular channel M conveying the liquids to a nozzle N through which they flow away.

The part F of the casing, cylindrical in 80 its lower half, runs up in two parallel sides in its second half, the top part of which is open and communicates with a piping O, bringing the parts to be pressed, the latter coming from a heater P, for instance.

The bed C carries a perforated plate Q, 85 the holes in which lead to vertical channels R which allow the liquids to escape outside the filtering casing.

Between the casing E and the plate Q is interposed a filtering fabric T, attached to 90 the two revolving drums S and S₁.

The upper drum S is driven by a known planet-gear, allowing by means of the braking of the drum U through a steel ribbon operated by the levers I¹ and H¹ of the 95 rotary motion of the pulley V¹ being transmitted to the shaft of the upper drum.

The lower drum S₁ turns loose on the bearings and receives the filtering fabric T, which it rolls up by means of the counter-weight V and of the cables X coiled round the axle y of the drum S.

A valve controller Z operates by cams on the pressure exhaust flaps of the pistons G and I.

105 It should be noticed that the pistons H and L are under constant pressure and only come into action when the pressure of the pistons G and I ceases.

Two trays A₁ and A₂ are slung under the 110

framework A, in order to receive the liquids which afterwards run, through the pipe B₁ into the channel C₁.

A sheet-iron box D₁, acting as conveying funnel for the oil-cake E₂, carries inside a flap F₁, maintained in its "closed" position by the springs G₁ and G₂.

H₂ is a rotary brush to clear the filtering fabric T at each motion.

10 The press may be doubled by fitting similar organs on both sides of the cylinder B, the latter containing in this case, two pressing pistons I opposed to each other and moving simultaneously in opposite directions.

The press acts as follows:

The metal casing E. F. being filled with the material to be pressed, the corresponding cam of the valve controller Z raises the pressure-admission flap-valve into the cylinder B.

20 The piston I enters part F of the casing, closes the inlet of the paste, enters part E of the casing, and there starts to strongly 25 compress the matter.

The liquid runs out through the perforated wall E₁ into the groove M and through the nozzle N into the tray A₁.

30 It also runs through the fabric T, through the holes of the plate Q, into the grooves R which drip into the tray A₂.

The time of the pressure being regulated by the speed of the cam-shaft of the valve controller Z, the cylinder B begins to empty 35 and the piston I goes back to its initial position, thus parting from the oil-cake made. As soon as this parting is completed, the valve controller Z, always by means of a cam, stops the hydraulic pressure on the 40 piston G and the casing E. F. slides back under the uninterrupted action of the piston H.

The backward movement of the casing E-F is quicker than that of the ram I; the 45 stop J₁ on this casing immediately pulling the levers I₁ and H₁, which clutch in the brake composed of a steel tape rolled on the pulley U.

50 The clutching of the pulley U allows the driving of the drum S, which pulls upwards the fabric T, thus raising the oil-cake into the funnel D₁; the fabric coiling itself round the drum S tears itself away from the oil-cake, the latter being maintained during its 55 upward motion in the funnel D₁, against the side d, tangential to the drums.

55 The oil-cake having passed the sloping flap F₁, the latter falls back, prompted by the springs G₁ and G₂ and the unhampered oil-cake rolls down the slope of F₁, which motion delivers it out of the apparatus.

The oil cake could also, by spontaneous parting from the fabric T, fall into the lower part.

During the ascending motion of the oil-cake, the fabric T forces, by means of the stop K₁, the arm I² and raises the lever I¹ which frees itself from the catch J₁. The pulley U is no longer driven, becomes loose and frees the drum S, which stops, and starts moving in the opposite direction, the fabric T moving backwards, under the action of the drum S₁, actuated by the counter-weight V.

65 The fabric T having returned to its starting position, the ram I, which was slowly sliding back, unmasks at this movement the inlet for the paste, whereas the valve controller Z sets in action the piston G, bringing the casing E. F. back against the bed C. 75

The paste falls into the casing and everything is now ready for another operating cycle as soon as the corresponding cam of the valve controller Z opens the flap-valve allowing pressure on the ram I.

85 Fig. 3 shows a different construction of part of the apparatus, the piston I being fitted with a perforated plate M₁ the holes in which lead into vertical channels thence into a circular groove N₁, from which the 90 liquids flow out of the casing, by way of the pipe O₁.

In this case a filtering fabric L₁ is fixed on the top part of the ram I; the matter is thus pressed between two layers of filtering 95 fabric placed on perforated metal surfaces.

In the upward motion of the oil-cake, the filtering fabric L₁ will loosen itself from it, by folding, as shown on Fig. 3.

The fabric L₁ will resume its position by 100 its own weight, as the fabric T returns into position.

I claim:

1. In an automatic hydraulically operated press for extraction of oil from seeds and 105 fruit, a ram, a movable pressure chamber for said ram, a bed for the pressure chamber carrying a perforated plate allowing liquid to escape from the pressure chamber, a filtering fabric arranged in front of the 110 perforated plate of the bed, means for moving said fabric to and fro upwards and downwards and from out of the pressure chamber, hydraulic means for moving said ram into the pressure chamber and withdrawing 115 from said chamber, hydraulic means for moving the pressure chamber to and fro, an inlet opening for material to be pressed provided in the wall of the pressure chamber and to be controlled by the ram, means 120 for admitting the hydraulic pressure onto the ram and onto the pressure chamber in such a way that first the ram is withdrawn from the cake and then the pressure chamber is removed from its bed thus enabling 125 the fabric to be pulled upwards together with the adhering oilcake, and means for controlling the motion of the fabric and giv-

ing it but once the to and fro motion only after the pressure chamber being removed from its bed.

2. In an automatic hydraulically operated press for extraction of oil from seeds and fruit, a ram, a movable pressure chamber for said ram, a bed for the pressure chamber, carrying a perforated plate allowing liquid to escape from the pressure chamber a filtering fabric arranged in front of the perforated plate of the bed, means for moving said fabric to and fro upwards and downwards and from out of the pressure chamber, hydraulic means for moving said ram into the pressure chamber and withdrawing from the latter, hydraulic means for moving the pressure chamber to and fro, an inlet opening for material to be pressed provided in the wall of the pressure chamber and to be controlled by the ram, means for admitting the hydraulic pressure onto the ram and onto the pressure chamber in such a way that the ram after having pressed the oil cake begins its backward motion first and then the pressure chamber is returning to its initial position whereby the speed of the pressure chamber exceeds the speed of the ram, thus enabling the fabric to be drawn upwards together with the adhering oilcake, and means for controlling the motion of the fabric and giving it but once the up and down motion only after the pressure chamber being removed from its bed.
3. In an automatic hydraulically operated press for extraction of oil from seeds and fruit, a ram, a movable pressure chamber for said ram, a bed for the pressure chamber, carrying a perforated plate allowing liquid to escape from the pressure chamber, a filtering fabric arranged in front of the perforated plate of the bed, means for moving said fabric upwards and from out of the pressure chamber, hydraulic means for moving said ram into the pressure chamber and withdrawing from the latter, hydraulic means for moving the pressure chamber to and fro, an inlet opening for material to be pressed provided in the wall of the pressure chamber and to be controlled by the ram, means for admitting the hydraulic pressure onto the ram and onto the pressure chamber in such a way that the ram after having pressed the oil cake begins its backwards motion first and then the pressure chamber is returning to its initial position whereby the speed of the pressure chamber exceeds the speed of the

ram, thus enabling the fabric to be drawn upwards together with the adhering oil cake, each end of the filtering fabric being fixed to a revolving drum, one of them arranged above and the other one arranged beneath the pressure chamber, the movement of the drums being controlled by stops pivotally mounted on the pressure chamber and means for driving the drums alternatively in both directions but only after the pressure chamber being removed from its bed.

4. In an automatic hydraulically operated press for extraction of oil from seeds and fruit, a ram having at its front end a perforated plate for the escape of liquid, a filtering fabric having one edge attached to the upper part of the front surface of the ram and laying against said front surface, a movable pressure chamber for said ram, a bed for the pressure chamber, carrying a perforated plate allowing liquid to escape from the pressure chamber, a second filtering fabric arranged in front of the perforated plate of the bed, means for moving said second fabric upwards and from out of the pressure chamber, hydraulic means for moving said ram into the pressure chamber and withdrawing from the latter, hydraulic means for moving the pressure chamber to and fro, an inlet opening for material to be pressed provided in the wall of the pressure chamber and to be controlled by the ram, means for admitting the hydraulic pressure onto the ram and onto the pressure chamber in such a way that the ram after having pressed the oil cake begins its backwards motion first and then the pressure chamber in returning to its initial position whereby the speed of the pressure chamber exceeds the speed of the ram, thus enabling the second filtering fabric to be drawn upwards together with the adhering oil cake, each end of the second filtering fabric being fixed to a revolving drum, one of them arranged above and the other one arranged beneath the pressure chamber, the movement of the drums being controlled by stops pivotally mounted on the pressure chamber and on the second filtering fabric and means for driving the drums alternatively in both directions but only after the pressure chamber being removed from its bed.

In testimony whereof I have affixed my signature.

LEON CHARLES DEOUNE.
